APPARATUS FOR CONTROLLING HIGHWAY CROSSING SIGNALS

Ralph R. Kemmerer, Swissvale, Pa., assignor to
The Union Switch & Signal Company, Swiss-
vale, Pa., a corporation of Pennsylvania

Application September 15, 1938, Serial No. 230,082

12 Claims. (Cl. 246—130)

My invention relates to apparatus for controlling highway crossing signals, that is, to means for controlling a signal of the type which is placed at the intersection between a railway and a highway for the purpose of warning users of the highway when a train is approaching.

It is essential that signals of this type be operated long enough in advance of the arrival of the train at the intersection to enable users of the highway to clear the intersection. It is desirable also that the signal not be operated too long in advance of the arrival of a train at the intersection as this unduly delays users of the highway and tends to create disrespect for the warning signal.

It is customary to initiate operation of a signal of this type when a train reaches a point in the track a predetermined distance from the intersection. This point is located far enough from the intersection so that on movement of a fast train over the track, the warning signal is operated for the proper time interval before the train reaches the intersection. On movement of a slow train over the track, if operation of the crossing signal is initiated when the train reaches the same predetermined point in the track, the signal will be operated for an unduly long period of time before the train reaches the intersection.

It is an object of my invention to provide a control system for a signal of the type described and incorporating means governed in accordance with the speed of the train traveling on the track for determining the time at which operation of the crossing signal is initiated to thereby maintain the period of operation of the signal substantially uniform irrespective of speed of the train approaching the intersection.

A further object of my invention is to provide improved apparatus of the type described and which does not necessitate the use of short track circuits.

Another object of my invention is to provide improved apparatus for controlling a highway crossing signal.

Other objects of my invention and features of novelty will be apparent from the following description taken in connection with the accompanying drawings, in which

Figs. 1A and 1B taken together are a diagram of a system embodying my invention.

Fig. 2 is an enlarged view showing a current transformer employed in the system shown in Figs. 1A and 1B.

Fig. 3 is a diagram of a modification of the system shown in Figs. 1A and 1B,

Fig. 4 is a fragmentary diagrammatic view showing a modified form of train detecting means embodying my invention.

Fig. 5 is a fragmentary diagrammatic view showing another modified form of train detecting means embodying my invention.

Fig. 6 is a fragmentary diagrammatic view showing a different form of a train detecting means embodying my invention.

Fig. 7 is an enlarged sectional view taken substantially along the line VII—VII of Fig. 6, and

Figs. 8 and 9 are fragmentary diagrammatic views showing still different forms of train detecting means provided by my invention.

Referring to Figs. 1A and 1B of the drawings, the reference character X designates a stretch of railway track over which traffic moves in both directions. The track stretch has rails 1 and 2 which are divided by insulated joints 3 into sections 1T and 2T, while the track stretch includes an intersection with a highway designated by the reference character H. The insulated joints 3 separating the track sections 1T and 2T are located adjacent the intersection.

The highway crossing H is protected by a signal S which may be of any suitable type, such as a bell or light signal or a combination of both. The signal S is controlled by a relay K which is of the type known as an interlocking relay and is provided with a pair of windings 5 and 6 which are responsive to the supply of alternating current.

The details of the construction of the interlocking relay K are not a part of the present invention and any suitable relay of this type may be employed. The relay K has a movable contact 7 controlled by the winding 5, and a movable contact 8 controlled by the winding 6. The contacts 7 and 8 are held in their open or picked up positions as long as the windings 5 and 6 are energized, while on deenergization of either of these windings the contact controlled by that winding is released and moves to its closed position in which it completes the circuit from one terminal B of a suitable source of current to the mechanism of the signal S. The mechanism of the signal S is directly connected to the other terminal C of that source of current.

The interlocking relay K is constructed in such a manner that when one winding of the relay is deenergized as a result of occupation of a track section by a train, and the contact controlled by that winding drops to its closed position, the movable contact controlled by the other winding is held in its open position so that when the

track section with which said other winding is associated becomes occupied and said other winding is deenergized, the contact controlled by the other winding is prevented from moving to its closed position.

The internal construction of the relay K is also such that if, while the second winding is deenergized, the first winding becomes energized as a result of movement of a train out of the track section with which the winding is associated, the movable contact controlled by that winding is caused to move from its closed to its open position, thereby interrupting the circuit to the mechanism of the signal S. When this contact picks up it continues to maintain the contact controlled by the other or second winding in its picked up or open position as long as the other winding is deenergized. When the other or second winding is again energized the control of the movable contact associated with that winding by the movable contact associated with the first winding is terminated, and on subsequent deenergization of the other winding at a time when the first winding is energized the movable contact associated with the other winding may move to its closed position.

The equipment associated with each of the track sections 1T and 2T for controlling the supply of current to a winding of the relay K is substantially the same as the equipment associated with the other track section. Accordingly only the equipment associated with the track section 1T at the left of the intersection H is shown in the drawings. It will be understood, however, that similar equipment is associated with the track section 2T at the right of the intersection H.

The track section 1T has associated therewith an alternating current track relay 1TR having a control winding 9 connected across the track rails 1 and 2 at a point adjacent the end of the track section 1T remote from the intersection H, while the local winding 10 of the track relay 1TR is connected by wires 12 and 14 to a suitable source of alternating current, such as a local commercial source of power, the terminals of which are designated by the reference characters BX and CX.

The track section 1T has associated therewith a track transformer 1TRA having its primary winding 15 connected to the wires 12 and 14, and thereby to the terminals BX and CX of the same source of alternating current as the local winding 10 of the track relay 1TR. The secondary winding 16 of the track transformer 1TRA is connected in series with a current limiting device, such as an impedance 17, with the track rails 1 and 2 at a point adjacent the end of the track section 1T adjacent the intersection H.

The track section 1T has associated therewith means for measuring the speed of a train traveling in such section to thereby determine the point in such section to which a train approaching the intersection H must advance before the circuit for supplying current to the winding 5 of the interlocking relay K is interrupted to thereby initiate operation of the crossing signal S.

As shown in the drawings, one terminal of the winding 5 of the relay K is connected to a branch of the wire 12, and thereby to the terminal CX of the source of alternating current. The other terminal of the winding 5 is connected by a wire 20 to a branch of the wire 14, and thereby to the terminal BX of the source of alternating current. The circuit through the wire 20 is controlled by train detecting apparatus associated with stations

A, B and C located at spaced points in the track section 1T and responsive to movement of a train through the track section.

Construction of train detecting means

The apparatus associated with the station A includes train detecting means incorporating current transformers A1 and A2 associated with the track rails 1 and 2. The construction of the current transformer A1 is shown in detail in Fig. 2 of the drawings. The current transformers employed at the various stations are all of similar construction and the construction of the transformer A1 only will be described in detail.

As shown in Fig. 2 of the drawings, the current transformer A1 comprises a generally U-shaped core member 22 which extends beneath the track rail 1 and has arms 23 and 24 extending upwardly adjacent the sides of the track rail. Suitable blocks 25 and 26 of non-magnetic material 20 are positioned between the arms 23 and 24, while a bolt 27 also of non-magnetic material extends through the arms 23 and 24, the blocks 25 and 26, and the track rail 1 to secure the core member 22 to the track rail.

The arm 23 of the core member 22 extends nearly to the top of the track rail 1. The arm 24 is located on the side of the track rail 1 adjacent the track rail 2, while the arm 24 is held by the block 25 spaced from the side face of the head 30 of the track rail a distance sufficient to enable the flange on a vehicle wheel to pass between the arm 24 and the rail. The core member 22 has mounted thereon a winding 29.

The windings 29 of the current transformers A1 and A2 are connected in series with each other, and in series with a condenser C1 with the primary winding 30 of a grid transformer AT6.

The station A has associated therewith a tube AV1 having a grid 32, an anode 33, and a cathode 34 in the form of a heated filament. These elements are mounted in a sealed envelope which is filled to a low pressure with a suitable inert gas. The tube AV1 is of the type known as a grid-glow tube and is characterized by the fact that the flow of current between the anode and the cathode of the tube is controlled by the relationship of the grid potential to the anode-cathode potential in such a manner that the tube is substantially non-conducting until the grid is given the proper potential in relation to the anode-cathode potential. When the grid is supplied with this potential the tube breaks down and becomes conducting.

One terminal of the secondary winding 36 of the grid transformer AT6 is connected to the anode 33 of the tube AV1, while the other terminal of the winding 36 is connected in series with a resistor or grid leak AR1 with the grid 32 of the tube AV1.

The filament or cathode 34 of the tube AV1 is connected to the terminals of the secondary winding 38 of the plate and filament transformer AT1. The primary winding 40 of the transformer AT1 is supplied with alternating current by branches of the wires 12 and 14. The grid 32 of the tube AV1 is connected in series with a grid condenser AC2 with a mid tap of the secondary winding 38 of the transformer AT1, and thereby with the cathode or filament 34.

The train detecting means at station A includes a direct current relay ARE1. One terminal of the winding of the relay ARE1 is connected to one terminal of the secondary winding 42 of the transformer AT1, while the other terminal

of the winding 42 is connected to the mid tap of the winding 38 of the transformer AT1 and thereby to the tube cathode 34. The other terminal of the winding of the relay ARE1 is connected in series with a current limiting resistor AR2 with the anode 33 of the tube AV1. A by-pass condenser AC3 is connected in multiple with the winding of the relay ARE1.

In operation, alternating current supplied from the wires 12 and 14 energizes the primary winding 40 of the transformer AT1, thereby causing current to be induced in the secondary windings 38 and 42. Current induced in the winding 38 is supplied to the filament 34 of the tube AV1 and heats this filament. Current induced in the winding 42 establishes a potential difference between the anode 33 and the cathode or filament 34 of the tube AV1.

The potential difference impressed between the anode and the cathode of the tube AV1 is less than the critical or breakdown value under conditions of zero or low grid potential. Accordingly, in the absence of greater than normal potential supplied to the tube grid, no current flows between the anode and the cathode of the tube and hence the relay ARE1 remains deenergized.

Alternating current is also supplied from the wires 12 and 14 to the primary winding 15 of the track transformer 1TRA, and from the secondary winding 16 of the transformer 1TRA current is supplied to the track rails 1 and 2.

The current which is supplied to one of the track rails of track section 1T flows through this rail to the other end of the track section, through the control winding 9 of the track relay TR to the other track rail, and thence through that track rail to the transformer 1TRA.

On the flow of current through the track rails magnetic lines of force are caused to flow in the magnetic core members 22 of the current transformers A1 and A2. As a result of the flow of these lines of force through the core members, current is induced in the windings 29 of these transformers.

The current which is induced in the windings 29 of the current transformers A1 and A2 is supplied therefrom to the primary winding 30 of the grid transformer AT6. On the supply of current to the winding 30 current is induced in the secondary winding 36 and flows therefrom to a circuit which includes the grid leak AR1, the grid condenser AC2, the winding 42 of the transformer AT1, by-pass condenser AC2, and resistor AR2.

The anode 33 of the tube AV1 is connected to this circuit at a point adjacent one terminal of the secondary winding 36. The grid 32 of the tube AV1 is connected to this circuit at a point intermediate the grid leak and the grid condenser, while the tube cathode 34 is connected by means of the center tap on the transformer secondary winding 38 to this circuit at a point on the side of the grid condenser AC2 remote from the point of connection of the grid 32 with the circuit.

As a result of this circuit arrangement when current is supplied to this circuit from the secondary winding of the transformer AT6, the potential on the grid is maintained at a value above that on the cathode, and the various circuits are arranged so that the potential difference between the grid and the cathode is in the same phase relationship as the potential difference between anode and the cathode.

The various parts of the apparatus are also ar-

ranged and proportioned so that when the track section is unoccupied, the value of the current supplied by the current transformers A1 and A2 to the grid transformer AT6 is such that the current supplied by the grid transformer to the grid circuit of the tube AV1 is sufficient to charge the tube grid 32 with a potential high enough to render the tube conducting.

Accordingly, on the supply of this potential to the grid 32 of the tube AV1, during the half-wave periods in which the polarity of the current in the circuit to which current is supplied by the secondary winding 42 of the transformer AT1 is such that the anode 33 of the tube AV1 is positive with respect to the cathode 34, current flows from the anode to the cathode, thereby effecting the flow of current in the circuit of the winding of the relay ARE1.

The flow of current from the anode 33 to the cathode 34 is interrupted during the half-wave periods in which the anode is negative with respect to the cathode. However, on subsequent reversal of the polarity of the current supplied by the secondary 42, the tube AV1 is again rendered conducting, provided the grid potential has been maintained at the proper value. The winding of the relay ARE1, therefore, is supplied with pulsating unidirectional current as long as the grid potential is maintained. On this supply of unidirectional current the winding of the relay is energized and the movable contacts of the relay are held in their picked up positions.

When the grid potential is reduced the tube becomes non-conducting and the supply of current to the winding of the relay ARE1 is interrupted with the result that the movable contacts of the relay ARE1 are released.

When a train is present in the track section and reaches a point at the right of the station A, the wheels and axles of the vehicles forming the train provide a shunt path between the track rails so that alternating current supplied to the track rails by the track transformer 1TRA may flow between the track rails through this shunt path, and does not flow in the portion of the track rails with which the current transformers A1 and A2 are associated. These transformers, therefore, will not supply current to maintain the grid potential of the tube AV1, and the tube will be rendered non-conducting while the relay ARE1 will be deenergized.

The relay ARE1 has a movable contact 45, which, when picked up, establishes the circuit through the wire 20 through which a connection is established from one terminal of the winding 5 of the interlocking relay K to a branch of the wire 14 and thereby to the terminal BX of the source of alternating current. When the relay ARE1 is released the contact 45 is open, thereby interrupting the supply of current through this contact and the wire 20, and thereby to the winding 5 of the interlocking relay K. On this interruption of the supply of current to the winding 5, the relay K will initiate operation of the crossing signal S unless the supply of current to the relay winding is established by other means.

The equipment associated with the station A includes timing means for establishing a connection independent of the relay ARE1 between the wire 20 and the wire 14 and thereby with the terminal BX if the time required for a train to traverse the distance from the entrance end of the track section to the station A exceeds a predetermined period.

Construction of timing means

The timing means included in the equipment associated with station A includes an electronic tube AV2, a relay ARE2, and a condenser AC4.

The tube AV2 is of a type having a pair of electrodes 47 and 48 mounted in a sealed envelope filled with an inert gas at a suitable pressure. The tube AV2 is of such character that it is non-conducting until the potential impressed across its terminals exceeds a critical value, while it remains conducting until this potential is reduced substantially below the critical value, whereupon it again becomes non-conducting.

The timing means includes a transformer AT2 having one terminal of its primary winding 50 connected by way of a wire 51 with a branch of the wire 12, and thereby with the terminal CX of the source of alternating current. This circuit of wire 51 is controlled by a contact 52 of the relay ARE2. When the contact 52 is in its released position it connects the wire 51 directly to a branch of the wire 12, while when the contact 52 is in its picked up position it connects the wire 51 to a wire 53 which is connected to the wire 12 by a contact 54 of the relay ARE1 when that contact is picked up.

The other terminal of the primary winding of the transformer AT2 is connected by way of a wire 55 with a movable contact 56 of the relay ARE1. When the contact 56 is picked up it connects the wire 55 to a wire 57 which is connected to the movable contact 58 of the track relay 1TR. When the track relay 1TR is de-energized its contact 58 is released and connects the wire 57 to a branch of the wire 14 and thereby to the terminal BX of the source of alternating current. When the contact of the track relay 1TR is released and the contact of relay ARE1 is picked up one terminal of the primary winding 50 of the transformer AT2 is connected to the terminal BX of the source of alternating current, while the other terminal of the winding 50 is connected to the terminal CX of the source of alternating current when the contact of relay ARE2 is released, or when the contact of relay ARE2 is picked up provided that the contact of relay ARE1 is also picked up.

The secondary winding 60 of the transformer AT2 is connected to the input terminals of a rectifier unit ARX1. One of the output terminals of the rectifier unit is directly connected to one side of the condenser AC4, while the other output terminal of the rectifier unit is connected in series with a resistor AR3 to the other side of the condenser AC4. A bridging resistor AR4 is shunted across the terminals of the condenser AC4, while a discharge resistor AR5 is provided and is constantly connected by a wire 62 with one side of the condenser AC4. The other terminal of the resistor AR5 is connected by a wire 63 with a stationary contact which is engaged by a movable contact 64 of the relay ARE1 when the contact is released. The contact 64 is constantly connected by a wire 65 with the side of the condenser AC4 other than that to which the wire 62 is connected. When the contact 64 of relay ARE1 is released, therefore, the discharge resistor AR5 is connected across the terminals of the condenser AC4 to discharge the condenser, while the discharge of the condenser is aided by the bridging resistor AR4.

The electrode 47 of the tube AV2 is connected to one side of the condenser AC4, and thus through the resistor AR3 to one of the output terminals of the rectifier ARX1, while the other

electrode 48 of the tube AV2 is connected to one terminal of the winding of the relay ARE2. The other terminal of the winding of the relay ARE2 is connected to the wire 62, and thereby to the other output terminal of the rectifier ARX1 and also to the other terminal of the condenser AC4.

The winding of the relay ARE2 being connected in series with the tube AV2 is maintained deenergized until the potential impressed on the tube is great enough to cause the tube to be rendered conducting, whereupon the relay winding is energized and the contacts of the relay are picked up.

The relay ARE2 has associated therewith means operative when the relay becomes picked up at a time when the relay ARE1 is released to establish a stick circuit to supply current to its own winding to maintain it picked up.

This means comprises a suitable source of supply of direct current which, as shown in the drawings, consists of a rectifier unit ARX2 which is supplied with current from the wires 12 and 14 by a transformer AT3. One of the output terminals of the rectifier ARX2 is connected to the wire 62, and thereby to one terminal of the winding of the relay ARE2. The other terminal of the rectifier unit ARX2 has connected thereto a wire 68 leading to a back point of contact of movable contact 69 of the relay ARE1. The contact 69 is connected by a wire 70 to a front point of contact of movable contact 71 of relay ARE2, while the contact 71 is connected to a terminal of the winding of relay ARE2.

When the relay ARE2 is picked up and the relay ARE1 is released, a stick circuit is established which is traced from one terminal of the relay winding through contact 71, wire 70, contact 69, and wire 68 to one side of the rectifier unit ARX2, while the other terminal of the relay winding is constantly connected by the wire 62 to the other terminal of the rectifier unit. Under these conditions the winding of the relay ARE2 will be energized by current supplied by the rectifier unit ARX2, and will remain picked up so long as this current supply is maintained.

The relay ARE2 has associated therewith means operative in the event that the relay becomes picked up before the relay ARE1 releases to establish a circuit shunting the resistance AR3 for supplying current from the rectifier unit ARX1 to the tube AV2 to thereby assist in maintaining the relay picked up. Referring to the drawings, it will be seen that a wire 14 is connected in series with a resistor AR6 with the conductor leading from one terminal of the rectifier unit ARX1 at a point on said conductor intermediate the rectifier terminal and the resistance AR3. The wire 14 is connected to the movable contact 75 of the relay ARE2. When the contact 75 is picked up it engages a stationary contact to which is connected a wire 76 which is also connected to a stationary contact which is engaged by the movable contact 64 of the relay ARE1 when that contact is picked up. The contact 64 is connected by way of the wire 65 with the electrode 47 of the tube AV2.

It will be seen, therefore, that when the contacts of both relays ARE1 and ARE2 are picked up, a circuit which shunts the resistance AR3 is established from the rectifier to the tube AV2. Current supplied by the rectifier ARX1 is accordingly supplied to the tube AV2 and also to the condenser AC4, with the result that the tube AV2 continues to be conducting, while adequate

current is supplied to the winding of the relay ARE2 to maintain the relay picked up. The resistor AR6 limits the current supplied through this circuit to a value sufficient to maintain the tube AV2 conducting once it has been started, but insufficient to cause the tube if not conducting to break down and become conducting.

Operation of timing means

- 10 On the supply of current to the primary winding 50 of the transformer AT2, current is supplied by the transformer secondary winding 60 to the input terminals of the rectifier unit ARX1, while current from the rectifier output terminals is supplied through the resistance AR3 to the opposite sides of the condenser AC4. In addition, one output terminal of the rectifier unit ARX1 is connected through the resistance AR3 to the electrode 47 of the tube AV2, while the other output terminal of the rectifier unit is connected by the wire 62 and the winding of the relay ARE2 with the electrode 48 of the tube AV2.
- 15 On the initial supply of current from the output terminals of the rectifier unit, the condenser AC4, being substantially without charge, absorbs the current supplied through the resistance AR3, with the result that the difference in potential at the two sides of the condenser is relatively small, while the difference in potential between the electrodes 47 and 48 of the tube AV2, which are connected in parallel with the sides of the condenser AC3, is likewise relatively small. At this time the difference in potential between the electrodes 47 and 48 of the tube is less than the 20 breakdown value of the tube with the result that current does not flow between the tube electrodes, and therefore does not flow through the winding of the relay ARE2 so the contacts of the relay ARE2 remain in their released position.
- 25 As a result of the supply of current to the opposite sides of the condenser AC4 the potential difference between the two sides of the condenser is increased, while there is a corresponding increase in the difference in potential between the electrodes 47 and 48 of the tube AV2.
- 30 After current has been supplied to the condenser AC4 for a predetermined time interval, the potential difference built up between the sides of the condenser, and also between the electrodes 35 of the tube AV2, is increased to a value exceeding the breakdown value of the tube AV2, whereupon current flows between the electrodes 47 and 48 of the tube and also through the winding of the relay ARE2 causing the contacts of the relay ARE2 to be picked up.

35 It will be seen, therefore, that on the supply of current to the transformer AT2, the relay ARE2 does not pick up instantaneously. Instead the operation of the relay is delayed for a period 40 of time determined by that required to build up a potential difference between the sides of the condenser AC4 equal to the breakdown value of the tube AV2.

Apparatus associated with stations B and C

45 The apparatus associated with station B is substantially a duplicate of that associated with station A and includes train detecting means responsive to the passage of a train in the track section, and it also includes timing means. The equipment at station C includes only train detecting means responsive to the passage of a train. The apparatus associated with the stations B and C is identified by the same reference 50 characters as are employed for the apparatus

at station A, except that the prefix A has been replaced by the prefix B or C. The construction and operation of the apparatus associated with the stations B and C are the same as the corresponding apparatus at station A and need not be 5 described in detail.

55 The stations A, B and C are located at spaced points throughout the track section 1T. The station A is spaced from the intersection H a distance such that if a train is approaching the intersection at a relatively high speed, as for instance in excess of 30 miles an hour, the highway crossing signal S should be started in operation when the train reaches the station A in order to give users of the highway proper warning of 10 the approach of the train.

60 The station B is spaced from the intersection H a distance such that when a train is approaching the intersection H at a medium speed, as for instance at a speed less than 30 miles an hour, 15 but greater than 20 miles an hour, operation of the crossing signal S should be initiated when the train reaches that station but not sooner.

65 Similarly, station C is spaced from the intersection H a distance such that if a train is approaching the intersection at a low speed, as for instance less than 20 miles an hour, the crossing signal S should be started to operate when the train reaches that station but not sooner.

70 The station C is located far enough from the intersection H so that if a train passes station B without initiating operation of the crossing signal, and then increases its speed, the crossing signal S, if started in operation when the train reaches station C, will operate for a sufficient 25 period of time before the train reaches the intersection.

Operation of system

75 The operation of the system as a whole will 40 now be described. It is assumed in this description that the track sections 1T and 2T are both unoccupied, that the signal S is deenergized, that the windings of the interlocking relay K are both energized, and that the other apparatus is in the 45 condition which it normally assumes when the track section is unoccupied.

80 Alternating current supplied from the terminals BX and CX of the source of alternating current supply flows through the wires 14 and 12 50 to the primary winding 15 of the track transformer 1TRA and to the local winding 10 of the track relay TR. On the supply of current to the primary winding 15 of the track transformer 1TRA, current is supplied from one terminal of 55 the secondary winding 16 to one of the track rails through which it flows to the other end of the track section, thence through the control winding 9 of the track relay TR, and through the other track rail to the other terminal of the secondary winding of the track transformer 1TR. The flow of current in this circuit is limited in the usual manner by the impedance 17 to prevent excessive current flow when the section is occupied.

85 On the supply of alternating current to both the local and the control windings of the track relay TR the movable contact 58 of this relay is held in its picked up position, thereby interrupting the circuit through the primary winding 70 50 of the transformer AT2 of the timing means located at station A.

90 On the flow of alternating current through the track rails 1 and 2, the current transformers A1 and A2, B1 and B2, and C1 and C2 associated 75

with the stations A, B, and C, respectively, supply current to the grid transformers at those stations to maintain the potential on the tube grids at a value high enough to cause these tubes to be conducting. Accordingly the windings of the relays ARE1, BRE1 and CRE1 are energized and the movable contacts of these relays are held in their picked up positions.

Each of the relays ARE1, BRE1 and CRE1 has a contact 45 controlling the circuit through the wire 20 leading to one terminal of the winding 5 of the interlocking relay K, the other terminal of which is connected to the terminal CX of the source of alternating current. When all of the contacts 45 are in their picked up positions a circuit is established from the winding 5 to a branch of the wire 14, and thereby to the terminal BX of the source of alternating current.

The winding 5 of relay K being energized holds the contact 7 in its picked up position, while the winding 6, being also energized by the circuit (not shown) associated with track section 2T, holds the contact 8 picked up with the result that the circuit to the signal S is interrupted.

At this time the relays ARE2 and BRE2 are both deenergized, while the condensers AC4 and BC4 associated therewith are substantially without charge.

Operation of system on passage of a slow train

A train traveling from left to right in the track stretch will enter the section 1T at the left-hand end. As soon as the train enters the track section 1T the wheels and axles of the vehicles comprising the train provide a circuit between the track rails shunting the control winding 9 of the track relay 1TR, thereby deenergizing the winding 9.

On deenergization of the winding 9 of the track relay 1TR the contact 58 thereof drops to its released position and engages its back contact, thereby establishing a circuit from the wire 14 to wire 57 leading to one terminal of the transformer AT2 at station A. As the relay ARE1 is energized and its contact 56 is picked up, wire 57 is connected to a terminal of primary winding 50 of transformer AT2. At this time the other terminal of the primary winding of transformer AT2 is connected to the wire 12 by the wire 51 and contact 52 of relay ARE2.

The circuit from the source of alternating current to the primary winding of transformer AT2 being complete as soon as the contact of relay 1TR becomes released, the transformer AT2 supplies current to the rectifier ARX1 which in turn supplies current to charge the condenser AC4. As soon, therefore, as a train enters the section 1T charging of the condenser AC4 of the timing means at station A is started and continues as the train advances in the track section towards station A.

Station A is located a substantial distance from the entrance end of the track section 1T and an appreciable period of time is required for a train to traverse the distance from the end of the track section to station A. The time required for the train to traverse this distance varies, of course, with the speed of the train.

The distance from the end of the track section to the station A, the capacity of the condenser AC4, the value of resistance AR3, the breakdown value of the tube AV2, and the values of other portions of the apparatus are selected and proportioned so that the difference in potential developed between the two sides of the condenser 75 will build up to a value in excess of the break-

down value of the tube AV2 before the train reaches station A if the train is traveling at a rate slower than 30 miles an hour, but so that the potential developed between the sides of the condenser AC4 will not be build up to the breakdown value of the tube AV2 before the train reaches station A if the train is traveling at a speed in excess of 30 miles an hour.

Since, therefore, the train is assumed to be traveling at a speed less than 30 miles per hour, 10 the tube AV2 will be rendered conducting before the train reaches station A. When the tube AV2 breaks down current flows through the winding of the relay ARE2 causing the movable contacts of this relay to be picked up.

When the contact 82 of the relay ARE2 is picked up a circuit is established through the contact 82 and a wire 83 to connect the wire 20 to a branch of the wire 14, and thereby to the terminal BX of the source of alternating current. Accordingly, on subsequent deenergization of the relay ARE1 and opening of its contact 45, the supply of alternating current to the winding 5 of the interlocking relay K will not be interrupted and the relay K will not start the crossing 25 signal S in operation.

As the relay ARE2 is energized before the train reaches station A, and, therefore, while the contacts of relay ARE1 are still picked up, a circuit which may be identified as the first stick 30 circuit is established which shunts the resistor AR3, to thereby increase the current supplied to the winding of the relay ARE2 and insure that its contacts will remain picked up. This circuit includes resistance AR6 and wire 74 leading from 35 one output terminal of the rectifier unit ARX1, contact 75 of relay ARE2, wire 76, contact 64 of relay ARE1, and wire 65. This first stick circuit has the resistance AR6 interposed therein which limits the current supplied to the tube AV2 to a 40 value sufficient to maintain conductivity of the tube, but not sufficient to cause the tube to break down and become conducting if the flow of current through the tube is not already established.

As the relay ARE2 remains energized the connection of the wire 20 to the branch of the wire 14 is maintained.

In addition, when the winding of the relay ARE2 is energized the movable contact 52 is 50 moved out of engagement with its back point of contact and into engagement with its front point of contact, thereby transferring the connection of the wire 51, leading from the primary winding 50 of the transformer AT2, to the branch of the 55 wire 12 by the wire 53 and the contact 54 of the relay ARE1.

As the train proceeds from left to right in the track section 1T, it will reach and pass the point at which the current transformers A1 and A2 60 are located, and the wheels and axles of the vehicle of the train will provide a shunt path between the rails so that substantially no current will flow in the portions of the track rails 1 and 2 adjacent the current transformers A1 and A2. 65

The transformers A1 and A2, therefore, will no longer supply current to the grid transformer AT6, while the grid transformer will no longer supply current to maintain the potential on the grid 32 of the tube AV1. The tube AV1, therefore, will be rendered non-conducting and the supply of unidirectional current to the winding of the relay ARE1 will be interrupted, with the result that the contacts of the relay ARE1 will be opened.

On deenergization of the relay ARE1 the contact 45 of this relay is opened, but its opening is without consequence as a circuit from the wire 14 to the wire 20 was established when the relay 5 ARE2 was energized.

On deenergization of the relay ARE1, the contact 64 closes, thereby completing a circuit for the winding of the relay ARE2 which was partially established when the contact 71 of relay 10 ARE2 was picked up. This circuit may be identified as the second stick circuit and supplies current from the rectifier unit ARX2 to the winding of the relay ARE2 to maintain this relay energized until the relay ARE1 is again energized.

15 In addition, on deenergization of the relay ARE1 the circuit of the primary winding 50 of the transformer AT2 is interrupted by the opening of contacts 56 and 54, and current, therefore, is no longer supplied by the rectifier unit 20 ARX1 to the condenser AC4 nor to the first stick circuit, and thus through the tube AV2 to the winding of the relay ARE2. The relay ARE2, however, remains energized by current supplied through the second stick circuit.

25 On deenergization of the relay ARE1 the contact 64 drops out of engagement with its front point of contact, thereby interrupting the first stick circuit. When the contact 64 engages its back point of contact, it completes a circuit between opposite sides of the condenser AC4 through the resistance AR5, this circuit being traced from one terminal of the condenser AC4 through wire 65, contact 64, wire 63, resistor AR5 and wire 62 to the other terminal of the condenser 30 AC4. This circuit provides means for dissipating any charge on the condenser AC4. The discharge of the condenser AC4 may also take place through the resistors AR3 and AR4, and to a limited extent through the rectifier unit ARX1. Accordingly, when the contacts of relay ARE1 are released the charge on the condenser AC4 is quickly dissipated so that the condenser is ready for another cycle of operation.

40 On the deenergization of the relay ARE1 the contact 80 closes, thereby connecting a branch of the wire 14 to the wire 57 leading from station A to the primary winding of the transformer BT2 of the timing means at station B. The relay BRE1 is assumed to be energized at this time with the result that its contact 56 is closed to connect wire 57 to the terminal of the transformer primary winding, while the other terminal of this transformer winding is connected to the wire 12 at this time. Accordingly, on closing 45 of the contact 80 of relay ARE1 at station A, which occurs as soon as the train advances in the track section to station A, the circuit through the primary winding of the transformer BT2 at station B is completed and this transformer supplies current to the rectifier unit BRX1 associated therewith, and the timing means at station B begins to measure the time required for the train to traverse the distance from station A to station 50 B, to thereby determine whether the operation of the crossing signal S should be initiated when the train reaches station B or should be delayed until the train reaches station C.

55 As pointed out above, it is assumed that the train is traveling at a slow speed, that is, less than 20 miles an hour. The time required for the train to traverse the distance from station A to station B is such that the difference in potential developed between the sides of the condenser BC4 at station B will exceed the breakdown value of

the tube AV2 before the train reaches station B, and the timing means at station B will operate in the manner described in detail in connection with station A to establish a circuit from the wire 14 to the wire 20 before the contact 45 of relay 5 ARE1 is released to interrupt the circuit controlled by it between the wire 20 and the wire 14.

Accordingly, when the train reaches station B and shunts the current in the track rails away from the current transformers B1 and B2 at station B and causes deenergization of the relay BRE1, the circuit to the winding 5 of the interlocking relay K is not broken and the relay K will not initiate operation of the signal S.

The equipment at station C does not include 15 timing means as it is unnecessary to measure the speed of the train traveling from station B to station C since it is desired that operation of the crossing signal S be started when the train reaches station C, if the signal has not previously 20 been placed in operation.

The equipment at station C includes train detecting means similar to that associated with stations A and B, and when a train advances in the track section 1T as far as station C, the relay 25 CRE1 is deenergized and its contact 45 breaks the circuit through which current is supplied to the winding 5 of relay K.

On deenergization of the winding 5 the contact 7 is released and completes the circuit to the crossing signal S, which thereupon operates to warn users of the highway of the approach of a train.

On movement of the train into the track section 30 2T, the apparatus (not shown) associated with that section operates to interrupt the circuit to the winding 6 of relay K. Because of the internal construction of the relay K, on deenergization of winding 6 at a time when winding 5 is deenergized and contact 7 is released, the contact 8 will not release to complete the circuit to the crossing signal S. Instead the contact 8 will be held in the open position and will remain in the open position on subsequent energization of the winding 5 and picking up of the contact 7 35 occasioned by movement of a train out of track section 1T. The contact 8 will be held in the open position following the picking up of contact 7 until the winding 6 is again energized which terminates control of the contact 8 by the contact 7. 40 Thereafter contact 8 is held in the open position due to energization of the winding 6, but will drop to the closed position on subsequent deenergization of the winding 6 while the winding 5 45 is energized.

Accordingly when the train vacates the track section 1T and the winding 5 is again energized, the interlocking relay K operates to cut off operation of the signal S.

55 As long as any part of the train is present in track section 1T a shunt path between the track rails is provided and little or no current flows through the rails 1 and 2 at stations A, B and C. Accordingly the current transformers at 60 these stations do not supply current to establish the grid potential necessary to render the tubes AV1, BV1 and CV1 conducting. The relays ARE1, BRE1 and CRE1, therefore, remain released, while the relays ARE2 and BRE2 remain energized. In addition the relay 1TR remains released.

65 When the train vacates track section 1T the shunt path between the track rails is removed and current supplied by the track transformer 70 75

'TRA again flows through the track rails 1 and 2 the entire length of the track section and energizes the control winding 9 of the track relay 'TR, causing the contact 58 thereof to be picked up, thereby preventing the supply of current to transformer AT2 on energization of relay ARE1.

In addition as a result of the flow of current through the track rails the current transformers 10 at stations A, B and C supply current to establish the grid potential on the tubes AV1, BV1 and CV1 and render these tubes conducting. When these tubes become conducting the relays ARE1, BRE1 and CRE1 are energized and pick 15 up their contacts.

On energization of relays ARE1, BRE1 and CRE1 following passage of a slow train through track section 'T, the contacts 45 thereof are closed to complete the circuit to the winding 5 20 of interlocking relay K.

On energization of relay ARE1 the movable contact 64 thereof is picked up, thereby interrupting the second stick circuit to the winding of 25 relay ARE2 through which current is supplied to the relay by the rectifier unit ARX2. On interruption of this stick circuit the relay ARX2 becomes released and its contact 82 interrupts the circuit from wire 14 to line 20, while its contact 71 30 interrupts the second stick circuit at another point. In addition, on the release of relay ARE2 the contact 75 interrupts the first stick circuit for the relay ARE2, while the contact 52 moves into engagement with its back point contact.

35 On energization of the winding of relay ARE1 contact 80 thereof is picked up to interrupt the supply of current to transformer BT2 at station B on energization of relay BRE2, while the contact 64 of relay ARE1 is picked up to open the 40 circuit through the resistor AR5. In addition, the contact 54 is picked up.

The various parts of the timing means associated with station A are accordingly restored to the initial condition and the timing means is 45 ready for another cycle of operation.

The timing means and the train detecting means associated with station B operate at this time in the same manner as that associated with station A, and the apparatus associated with the 50 track section 'T is conditioned to respond to the passage of another train.

Operation of system on passage of a fast train

55 The operation of the system in response to the passage of a slow train having been described, the operation of the system in response to passage of a fast train will now be described.

On entrance of a fast train into the track section 'T from the left, the track relay 'TR is 60 released as before, and the circuit to the primary winding 50 of the transformer AT2 is completed. Current, therefore, will be supplied by the rectifier unit ARX1 through the resistor AR3 to the condenser AC4.

As the train is traveling at a rapid rate, as for instance in excess of 30 miles per hour, the time required for the train to traverse the distance from the entrance of the track section to station 70 A is less than that required to build up the difference in potential on opposite sides of the condenser AC4 to a value great enough to cause the tube AV2 to break down and become conducting. Accordingly the relay ARE2 will still be released 75 when the train reaches station A and effects op-

eration of the train detecting means at that station to cause the relay ARE1 to be released.

On release of relay ARE1 before the relay ARE2 has become energized, the contact 45 of the relay ARE1 is opened, thereby cutting off the connection from wire 20 to wire 14. As the relay ARE2 is still released there is no circuit between the wire 20 and the wire 14 through the contact 82 of the relay ARE2. Accordingly, the circuit through the winding 5 of the interlocking relay K 10 is interrupted and the movable contact 7 of relay K is released, thereby completing the circuit to the signal S and initiating operation of the signal.

It will be seen, therefore, that on movement of a fast train through the track stretch, operation of the crossing signal is initiated as soon as the train reaches station A, which is far enough removed from the highway intersection to cause the signal to be operated for the proper interval of time before the train reaches the highway crossing, even though the train is traveling at a high rate of speed.

On the release of the relay ARE1 prior to 25 energization of the relay ARE2 the contact 56 of the relay ARE1 is opened, thereby cutting off the supply of energy to the transformer AT2 with the result that current is no longer supplied to increase the potential difference between the two sides of the condenser AC4, which, as previously stated, was insufficient to render the tube AV2 conducting.

30 In addition, on the release of the relay ARE1, the contact 64 drops into engagement with its 35 back point of contact with the result that a circuit is established from the opposite sides of the condenser AC4 through the resistor AR5. Accordingly the charge on the condenser AC4 may be discharged by flow of current through the resistor AR5, as well as by flow through the resistors AR3 and AR4. The charge on the condenser AC4 will be quickly and completely dissipated so that on the subsequent supply of current to the condenser the time required to build up the potential difference between the sides of 45 the condenser will not be reduced by the presence of a partial charge on the condenser.

On the release of the relay ARE1 the contact 80 thereof is closed, thereby establishing connection from a branch of the wire 14 to the wire 50 57 leading to the transformer BT2 at station B. At this time the relay BRE1 of the train detecting means at station B is energized, and its contact 56 completes the circuit from wire 57 to transformer BT2 so that when the contact 80 of relay ARE1 closes current is supplied to the primary winding of transformer BT2.

55 On the supply of current to the transformer BT2 current is supplied by the rectifier unit BRX1 to the condenser BC4 to build up the charge on this condenser. However, before enough time has elapsed for the charge on the condenser BC4 to be built up to a value high enough to render the tube BV2 conducting, the train will have traversed the distance from station A to station B, and the train detecting means at station B will be operated as described in connection with station A to interrupt the supply of current to the condenser BC4 of the timing means at station B and to dissipate the charge built up 65 on that condenser.

Furthermore, the relay BRE1 at station B will be deenergized and the contact 45 thereof will interrupt the circuit through the wire 20, while the relay BRE2 will not be operated to estab-

lish connection from the wire 14 to the wire 20, and the winding of the interlocking relay K will continue to be deenergized and effect operation of the signal S.

5 At the time of the opening of the contact 45 of relay BRE1, the circuit through the wire 20 was already interrupted at the contact 45 of the relay ARE1 so the deenergization of relay BRE1 was without consequence since the winding 5 of 10 interlocking relay K was already deenergized.

Similarly when the train reaches station C the relay CRE1 is deenergized and its contact 45 interrupts the circuit through the wire 20 at another point.

15 When the train advances into track section 2T the equipment (not shown) associated with that section is operated to interrupt the circuit through the winding 6 of the interlocking relay K, but because of the internal construction of 20 the relay K, the contact 8 will not drop to its closed position.

When the rear of the train vacates the track section 1T the shunt path between the track rails provided by the wheels and axles of the vehicles 25 comprising the train is no longer present. Accordingly the current supplied by the track transformer 1TRA again flows the entire length of the track rails of the track section 1T with the result that the track relay 1TR becomes picked up, 30 while the relays ARE1, BRE1 and CRE1 also are again energized and the apparatus is conditioned to respond to the passage of another train through the track stretch.

The operation of the system in response to the 35 passage of a slow train and of a fast train having been explained, the operation of the system on the passage of a train of medium speed, that is at a speed below 30 miles an hour but above 20 miles an hour, will now be explained.

40 *Operation of system on passage of a train at medium speed*

On entrance of the train into the track section 1T from the left, the track relay 1TR will 45 be deenergized as before, and the contact 58 will complete the circuit through the wire 57 to the timing means at station A. The condenser AC4 will have current supplied thereto, and since the train is assumed to be traveling at medium speed, 50 the potential between the two sides of the condenser will be built up to a value exceeding the breakdown value of the tube AV2 before the train reaches station A.

Accordingly the relay ARE2 will be energized 55 and its contact 82 will establish a circuit from the wire 14 to the wire 20 before contact 45 of the relay ARE1 is released to interrupt the circuit between the wires 14 and 20 which it controls. The supply of current to the winding 60 5 of the interlocking relay K will be maintained, and operation of the signal S will not be initiated until the train advances farther into the track section.

On the release of relay ARE1 the circuit 65 through the wire 57 to the transformer BT2 of the timing means at station B is completed and the supply of current to the condenser BC4 is started. The distance between the stations A and B is such that a train traveling at a medium speed will traverse the distance between the stations A and B before the condenser BC4 is charged to a value high enough to cause the tube BV2 to break down and become conducting.

70 Accordingly the train will reach station B and

cause deenergization of relay BRE1 before the relay BRE2 has become energized. On this deenergization of the relay BRE1 its contact 45 interrupts the circuit through the wire 20 to the interlocking relay K with the result that 5 the winding 5 of relay K is deenergized and contact 7 becomes released to initiate operation of the signal S, while the supply of current to the condenser BC4 is interrupted and a circuit through the resistance BR5 is established to dissipate the charge built up on the condenser.

It will be seen, therefore, that on the passage of a train of medium speed through the track section the crossing signal S will be maintained inoperative until the train reaches station B, 15 whereupon operation of the signal will be initiated.

20 *Operation of system during movement of train in reverse direction*

The system provided by my invention is arranged so that on movement of a train through the track stretch in the reverse direction, that is from right to left, the equipment associated with the track section will be automatically restored to its normal condition on departure of the train from the track section.

If a train is traveling in the track stretch from right to left, the equipment (not shown) associated with section 2T will be operated as 30 described above in connection with the apparatus associated with section 1T to interrupt the circuit to the winding 6 of the relay K so that this relay will effect operation of the signal S.

On entrance of the train into track section 35 1T, a shunt path between the track rails is provided with the result that the track relay 1TR is deenergized, while the tubes AV1, BV1 and CV1 of the train detecting means at stations A, B and C are rendered non-conducting because of the interruption of the supply of current to maintain their grid potential. The relays ARE1, BRE1 and CRE1, therefore, are deenergized and the circuit through the wire 20 to the winding 5 of the relay K is interrupted by 45 each of these relays.

In addition on release of contacts 56 of relays ARE1 and BRE1, the circuits of the primary windings of transformers AT2 and BT2 are interrupted and no current will be supplied to 50 the condensers AC4 and BC4.

Because of the internal construction of the relay K, on this deenergization of the winding 5 at a time when the winding 6 is deenergized, the contact 7 does not drop to its closed position, but is held in its open position.

As the train proceeds through the track stretch the rear of the train will successively pass the stations C, B and A. When the rear of the train is located at the left of station C, current 60 supplied by the transformer 1TRA again flows through the portions of the track rails 1 and 2 on which are mounted the current transformers C1 and C2, with the result that the grid potential of the tube CV1 is reestablished and this tube 65 is again rendered conducting. The relay CRE1 will, therefore, be energized and the contact 45 will be closed.

Similarly, when the train has progressed to a point at which the rear of the train is located at 70 the left of the station B, the tube at that station will be rendered conducting and the relay BRE1 will be energized and its contact 45 will be closed, while its contact 56 will also be closed. At this time, the relay ARE1 being deenergized and its 75

contact 80 being closed, closure of contact 56 of relay BRE1 completes the circuit to the transformer BT2 of the timing means at station B with the result that current is supplied to the 5 condenser BC4.

If the train is traveling slowly, or should stop before the rear of the train has advanced to a point at the left of station A, the condenser BC4 will be charged to a value exceeding the break-down value of tube BV2 and this tube will be rendered conducting and will cause the relay BRE2 to be energized. On this energization of the relay BRE2, the contact 82 thereof is closed and completes a circuit from wire 14 to wire 20, 10 and thence to the winding 5 of the interlocking relay K. On this energization of the relay BRE2 at a time when the relay BRE1 is energized, the first stick circuit for the winding of relay BRE2 is established. This circuit includes resistance 15 BR6, wire 14, contact 75, wire 16, contact 64, and wire 65. At this time as the relay BRE1 is energized the second stick circuit for the relay BRE2, that is the circuit through which current is supplied from rectifier BRX2, is not completed. 20 25 On further movement of the train so that the rear of the train is located at the left of the station A, the relay ARE1 becomes energized, with the result that its contact 56 closes and completes the circuit to the transformer AT2, while the contact 80 is picked up and opens the circuit to the primary winding of the transformer BT2 at station B. In addition, the contact 45 of relay ARE1 is closed, thereby establishing connection from the wire 14 to the wire 20, so that the circuit 30 35 through the winding 5 of interlocking relay K is maintained after relay BRE2 releases.

When the relay ARE1 picks up and interrupts the circuit to the primary winding of transformer BT2 the supply of current by that transformer 40 to the rectifier unit BRX1 is cut off. The supply of current from the rectifier unit to the first stick circuit for the winding of relay BRE2 is likewise cut off and the relay BRE2 releases, thereby breaking the stick circuit, while the contact 82 45 opens to interrupt the connection which it establishes between the wires 14 and 20. However, before this occurs a connection between these wires is established by the contact 45 of relay ARE1 so that the supply of current to the winding 5 of interlocking relay K is maintained. 50

If the train is moving slowly while the rear of the train is in the section between station A and the left-hand end of track section 'T, or if the 55 train should stop while the rear of the train is in this portion of the track section, the timing means associated with station A will operate in the manner described in connection with station B. When the train passes out of the track section, the track relay 'TR picks up, thereby opening the circuit through the primary winding 50 of transformer AT2 with the result that the relay ARE2 releases if it has become picked up.

The charge built up in the condensers AC4 and 60 BC4 is dissipated through the resistors R3 and R4 associated therewith so that on subsequent movement of a train through the track stretch from left to right the timing means associated with stations A and B will accurately measure 65 the speed of the train.

It will be seen, therefore, that as soon as the train traveling from right to left passes out of the track section, the equipment for controlling the crossing signal is restored to its normal condition, and is prepared to respond to the passage 70 75

of a train through the track section from left to right.

Operation of system in response to movement of two trains

5

The equipment provided by my invention is arranged in such a manner that in the event that a train approaching the highway crossing enters the track section before another train traveling in the same direction has vacated the 10 section, the crossing signal will be operated for the proper interval of time before the second train reaches the intersection.

As a result of the movement of the first train through the track section 'T, it being assumed 15 that the rear of this train remains in the track section, the flow of current in the portions of the track rails at the stations C, B and A is interrupted with the result that the tubes CV1, BV1 and AV1 of the train detecting means at these 20 stations are rendered non-conducting. The relays CRE1, BRE1 and ARE1 at these stations, therefore, are deenergized and the interlocking relay K is conditioned to effect operation of the 25 signal S.

The relays ARE2 and BRE2 associated with timing means at stations A and B may be energized or deenergized depending upon the speed at which the first train was moving when it entered the track section. For purposes of illustration it will be assumed that the first train was traveling at a medium speed with the result that the relay ARE2 is energized, while the relay BRE2 is not energized. 30

With the equipment in this condition, and with the rear of the first train located at a point in the track section 'T adjacent the intersection H, it will be assumed that a second train traveling from left to right, enters the track section 'T. The second train will necessarily be moving at a slow speed when it enters the section 'T, since the wayside signal, not shown, at the entrance to this track section or adjacent thereto will indicate that the section is occupied. 35 40

At the time the second train enters the track section 'T, the track relay 'TR is released due to the presence of a portion of the first train in the track section. The entrance of the second train into the track section, therefore, does not cause any change in the condition of the equipment associated with the track section. 45 50

It will be assumed that the first train has continued its movement so that the rear of that train vacates the track section 'T after the second train enters the track section 'T, but before the second train reaches station A. 55

In the interval between the time at which the second train enters and the first train vacates the track section, the tube AV1 is non-conducting and the relay ARE1 is deenergized with the result that contact 56 of relay ARE1 is open and interrupts the circuit of the primary winding 50 of transformer AT2. The relay ARE2 is assumed to be energized at this time. Since the relay ARE2 is energized, and the relay ARE1 is deenergized, the winding of the relay ARE2 is supplied with current by the rectifier unit ARX2 through the second stick circuit. 60 65

At this time, as the relay ARE1 is released, the contact 64 thereof establishes a circuit through the resistance AR5 so that any charge which had been impressed on the condenser AC4 will have been dissipated and the condenser is, therefore, substantially without charge. 70 75

When the first train vacates the track section

!T, current supplied by the track transformer !TRA is again present in the track rails at stations A, B and C and the relays RE1 of the train detecting means at these stations are again energized with the result that their contacts 45 are closed and complete the circuit to the winding 5 of the interlocking relay K. The relay K thereupon interrupts operation of the crossing signal S.

10 When the relay ARE1 picks up, its contact 69 breaks the second stick circuit of the relay ARE2 so that the relay ARE2 releases.

In addition, on the picking up of relay ARE1 its contact 56 is closed, thereby completing the 15 circuit to primary winding 50 of the transformer AT2 since the track relay !TR is released due to the presence of the second train in the track section. The circuit through the primary winding of the transformer AT2 is completed regardless of whether the relay ARE2 is released 20 or is picked up. If the relay ARE2 is released, the wire 51 leading from one terminal of the primary winding 50 of transformer AT2 is connected by the contact 52 directly to a branch of the wire 12. If the relay ARE2 is picked up, the wire 51 is connected by the contact 52 to the wire 53, which at this time is connected by the contact 54 of the relay ARE1 to a branch of the wire 12. Accordingly when the relay ARE1 picks 25 up, current is supplied to the primary winding of the transformer AT2, with the result that current is supplied by the transformer to the rectifier unit ARX1, and by that unit to the condenser AC4. As the charging of the condenser 30 is started promptly on the departure of the first train from the track section, the timing means associated with station A will make the most accurate determination possible of the speed of the second train.

40 On the picking up of the relay ARE1, if the relay ARE2 has not released but has been maintained energized by current supplied by the rectifier ARX2 through the second stick circuit, the contact 64 of the relay ARE1 will complete the 45 first stick circuit for the winding of the relay ARE2 to which current is supplied by the rectifier unit ARX1. The flow of current in this circuit is limited by the resistor AR6 to a value insufficient to cause the tube AV2 to break down 50 and become conducting. Accordingly the supply of current to this circuit will not effect energization of the relay ARE2 and cause the relay to remain picked up. On picking up of relay ARE1 and interruption of the second stick circuit by its contact 69 the relay ARE2 will, therefore, release if it has not already released.

When the relay ARE2 releases, its contact 82 opens, thereby breaking the circuit which it controls between the wire 14 and the wire 20.

60 When the relay ARE1 picks up, its contact 80 is opened, thereby interrupting the circuit from the wire 14 to the wire 51 leading to the transformer BT2. Accordingly the picking up of contact 56 of relay BRE1 will not establish a circuit 65 to the transformer BT2 and current will not be supplied to the condenser BC4, while the relay BRE2, which was assumed to be deenergized, will remain deenergized.

As the second train advances in the track section, the condenser AC4 is being charged, and since the second train is traveling relatively slowly, the condenser AC4 will probably be charged to a value high enough to cause the tube AV2 to break down and energize the relay ARE2 before 75 the train reaches the station A, even though the

train had traversed a portion of the distance from the end of the track section to the station A before the charging of the condenser AC4 was begun. If this sequence of operation occurs, and the relay ARE2 is energized before the relay 5 ARE1 is deenergized, the contact 82 of the relay ARE2 will close and establish a circuit between the wire 14 and the wire 20 before the contact 45 of the relay ARE1 opens. Accordingly the circuit to the winding 5 of the interlocking relay 10 K is maintained and operation of the crossing signal S is not started when the train reaches station A and causes deenergization of the relay ARE1.

15 However, as the train continues to advance in the track section !T, operation of the crossing signal S will be initiated, in the manner heretofore described in detail, when the train reaches station B or C depending upon the speed at which 20 the train is moving.

If the second train is traveling at a relatively rapid rate when it enters the track section !T, or if it is traveling at a relatively slow speed and should advance a substantial part of the distance from the entrance end of track section !T to the 25 station A before the first train vacates the track section and charging of the condenser AC4 at station A is initiated, the second train may reach station A and cause deenergization of the relay ARE1 before the condenser AC4 is charged up 30 sufficiently to cause the relay ARE2 to be energized.

If this sequence of operation occurs, when the relay ARE1 becomes deenergized its contact 45 opens the circuit to the winding 5 of the interlocking relay K, and the relay K thereupon starts 35 the signal S in operation. The start of the operation of signal S will occur somewhat sooner than is necessary to provide a warning of the proper duration since the relatively slowly moving train will require more time to traverse the distance from station A to the intersection H than is required by the trains which normally initiate operation of the crossing signal when they reach station A. A somewhat longer than 40 45 normal period of operation of the crossing signal under these conditions is not objectionable, and is preferable to a shorter than normal period of operation of the warning signal.

50 It will be seen, however, that the applicant's system is arranged so that the possibility of operation of the signal for an abnormal period of time is reduced to a minimum. As previously pointed out, when the relay ARE1 picks up following the departure of the first train from the track section, a circuit is established through the primary winding of the transformer AT2 irrespective of whether the relay ARE2 has released or is picked up. Accordingly the charging of 55 the condenser AC4 is started promptly on the departure of the first train, with the result that current is supplied to the condenser AC4 for the maximum period of time possible under the circumstances, with the resultant maximum probability that the condenser will be charged sufficiently to effect energization of the relay ARE2 before the second train reaches station A.

Operation of system on entrance of train in track section and subsequent exit of train in opposite direction

The system provided by my invention is arranged so that, if a train enters the track section, stops and then departs from the track sec- 75

tion at the same end as that at which it entered, the apparatus comprising the system will automatically restore itself to the proper condition to respond to the passage of another train through 5 the track section.

For the purpose of illustration it will be assumed that a train enters the track section $1T$ from the left, advances a part of the length of the track section, stops and then departs from 10 the left-hand end of the track section.

When the train enters section $1T$, the track relay $1TR$ becomes released and the circuit to transformer $AT2$ is completed so that charging of the condenser $AC4$ is started. Since the train 15 is about to stop, it will not be traveling rapidly enough to reach station A before the condenser $AC4$ is charged sufficiently to effect energization of relay $ARE2$. The relay $ARE2$, therefore, will maintain the circuit to the interlocking relay K and thereby prevent operation of the crossing signal S if the train advances beyond station A. 20

If the train passes station A, the relay $ARE1$ will be released and will effect the supply of current to the transformer $BT2$ to thereby start 25 charging of the condenser $BC4$. If the train stops before reaching station B, the condenser $BC4$ will become charged up and effect energization of the relay $BRE2$, while the relay $BRE1$ will remain energized with the result that its contact 30 69 interrupts the second stick circuit for relay $BRE2$ and the relay $BRE2$ will not be energized by current supplied over this circuit.

On subsequent reverse movement of the train so that the end of the train is located at the left 35 of station A, the relay $ARE1$ picks up, thereby cutting off the supply of current to the transformer $BT2$. As a result the relay $BRE2$ becomes deenergized, while the charge built up in the condenser $BC4$ is dissipated through the resistors 40 $BR3$ and $BR4$.

When the relay $ARE1$ picks up, the supply of current to the transformer $AT2$ is reestablished and charging of the condenser $AC4$ is again effected. When the train departs from the track 45 section $1T$, the track relay $1TR$ is again energized and its contact 58 becomes picked up, thereby interrupting the supply of current to the transformer $AT2$ with the result that the relay $ARE2$ becomes released if it became energized, while the 50 charge built upon the condenser $AC4$ is dissipated through the resistors $AR3$ and $AR4$. The equipment associated with track section $1T$ is now in its normal condition. The relays of the 55 train detecting means are energized, while the relays of the timing means are deenergized and the condensers associated therewith are discharged. The equipment, therefore, is conditioned to respond to the passage of another train through the track stretch.

60 The system provided by my invention is arranged so that a failure of any portion of the apparatus to function in its intended manner will result in operation of the crossing signal rather than in the failure of the signal to operate.

65 If for instance the tube associated with one of the train detecting means should become inoperative for any reason, such as failure of its filament, the relay associated with that tube would be deenergized and would interrupt the circuit 70 to the interlocking relay, thereby causing that relay to effect operation of the crossing signal.

Likewise, if the tube of one of the timing means should be rendered inoperative and failed to become conducting, the relay associated with that 75 tube would remain deenergized and would not

establish the circuit which it controls to connect the wire 14 to the wire 20 . As a result the circuit to the interlocking relay K will be interrupted somewhat sooner than it normally would be and the crossing signal will be operated for longer 5 than its usual period.

Similarly, if any of the other portions of the timing means should fail to function as intended, the effect would be to prevent energization of the 10 relay of that means with consequent operation of the crossing signal sooner than would occur if the timing means functioned in its normal manner.

Furthermore, if the track circuit, the current 15 or grid transformers, the track transformer or the associated apparatus should fail to function as intended, the grid potential on the tubes of the train detecting means would not be maintained. These tubes would thereby be rendered non-conducting with resultant deenergization of the 20 relays controlled thereby and interruption of the circuit to the interlocking relay K .

It will be seen, therefore, that the system incorporates important safety features so that 25 failure of operation of the warning signal as a result of failure of the apparatus of the control system is avoided.

In addition it will be seen that the system is arranged in such a manner that cut sections in 30 the track rails are unnecessary at the various stations at which the train detecting means are located. This is an important advantage, particularly if the system is applied to an electrified railroad where cut sections necessitate expensive impedance bonds to carry the propulsion 35 current between adjacent sections.

Furthermore, it will be seen that the system provides means responsive to the speed of the train approaching the intersection for determining the point to which the train must advance 40 before operation of the crossing signal is initiated in order that the period of operation of the signal prior to the arrival of the train at the intersection will be substantially the same irrespective of the speed of the train. 45

Construction and operation of the modification shown in Fig. 3 of the drawings

In Fig. 3 of the drawings I have shown means for adapting the system shown in Figs. 1A and 50 1B for use on an electrified railway employing alternating current for propulsion purposes. The modification shown in Fig. 3 incorporates means to prevent the propulsion current flowing in the track rails from causing the current transformer 55 to supply current to the associated grid transformer which might result in the supply of current to the grid of the tube associated with the grid transformer. If this condition arose, the tube might be rendered conducting at a time when 60 it is intended that the tube be non-conducting.

As shown in Fig. 3 of the drawings, a condenser 90 and a reactance 91 are connected in series between the wires leading from the current transformers $A1$ and $A2$. The values of the condenser 90 and the reactance 91 are chosen with respect to the values of the rest of the circuit so that the condenser and the reactance together with the current transformers $A1$ and $A2$ form a circuit which is resonant to the 25 cycle propulsion current, but is not resonant to the 60 cycle current supplied to the track rails by the track transformer associated with the crossing signal control apparatus. Accordingly any current induced in the current transformers $A1$ and $A2$ by the 25 75

cycle propulsion current will be absorbed by the reactance 91 and the condenser 90, thereby preventing undesired supply of current to the tube grid circuit. The reactance 91 and condenser 90, however, will not interfere with the supply of 60 cycle current to the tube grid circuit. The tube, therefore, will be rendered conducting in response to the flow of 60 cycle current in the track rails, but will not be rendered conducting as a result of the flow of 25 cycle propulsion current in the track rails.

Construction and operation of the modification shown in Fig. 4 of the drawings

15 In Fig. 4 of the drawings I have shown a portion of a system embodying my invention and incorporating a modified form of train detecting means.

20 The system shown in Fig. 4 of the drawings is the same as that shown in Figs. 1A and 1B, except as hereinafter pointed out in detail, and the same reference numerals are employed in Fig. 4 as are employed in Figs. 1A and 1B to designate the structure found in Fig. 4 which is common 25 to the system shown in Figs. 1A and 1B.

The system shown in Fig. 4 of the drawings differs from that shown in Figs. 1A and 1B of the drawings in that the system shown in Fig. 4 necessitates the use of insulated joints in the 30 track rails at the various train detecting stations, and is intended for use in non-electrified territory where alternating current track circuits for controlling the signals are not employed. The system shown in Fig. 4 further differs from that 35 shown in Figs. 1A and 1B as the system shown in Fig. 4 employs a tube of the cold cathode type, while the system shown in Figs. 1A and 1B employs a tube of the hot cathode type.

40 Referring to Fig. 4 of the drawings, the track rails 1 and 2 of the track section have insulated joints 3 therein defining one end of the track section 1T, while the track rails 1 and 2 also have insulated joints 3a therein at the station A, as well as at stations B and C, not shown. The 45 track section 1T has associated therewith a track relay 1TR of the type employed in the system shown in Figs. 1A and 1B. This relay has a local winding 10, and has a control winding 9 connected across the track rails of the track section 1T. A track transformer, not shown, similar to that shown in Figs. 1A and 1B is connected 50 across the track rails 1 and 2 adjacent the other end of the track section 1T.

The train detecting means at station A includes 55 a tube AV1a of the cold cathode type comprising a grid 32a, an anode 33a, and a cathode 34a mounted in a sealed envelope filled with an inert gas at a low pressure. The tube AV1a has associated therewith a transformer AT1a, the 60 primary winding 40a of which is supplied with alternating current from the same source as the track transformer, not shown. The tube AV1a also has associated therewith a relay ARE1, one terminal of the winding of which is connected to 65 one terminal of the secondary winding 42a of the transformer AT1a. The other terminal of the transformer secondary winding 42a is connected to the cathode 34a of the tube AV1a, while the other terminal of the relay winding is connected 70 in series with a resistance AR2 with the anode 33a of the tube AV1a. A condenser AC3 is shunted across the terminals of the relay winding.

The equipment at station A includes a transformer ATa having a primary winding 100 con-

nected across the track rails 1 and 2 on the side of the insulated joints 3a at station A adjacent the track transformer, not shown, associated with track section 1T. The transformer ATa has a secondary winding 101 connected across the track 5 rails 1 and 2 on the side of the insulated joints 3a at station A opposite from that on which the primary winding 100 is connected.

The transformer ATa has another secondary winding, indicated at 102, one terminal of which 10 is connected to the anode 33a of the tube AV1a, while the other terminal of the winding 102 is connected in series with a resistor AR1a with the tube grid 32a. A condenser AC2a is connected 15 between the grid 32a and the cathode 34a.

In operation current supplied by the track transformer, not shown, to the track rails 1 and 2 flows through the primary winding 100 of the transformer ATa and induces current in the secondary windings 101 and 102. Current induced 20 in the secondary winding 101 is supplied to the track rails 1 and 2 at the left of station A and flows through these rails and energizes the control winding 9 of the track relay 1TR.

If there are any other train detecting stations, 25 such as those identified at B and C in Figs. 1A and 1B intermediate the station A and the track transformer, the current supplied by the track transformer will be supplied around the insulated joints at these stations through the transformers 30 in the manner described above.

The current in primary winding 100 of transformer ATa also induces current in winding 102 with the result that current is supplied through the resistor AR1a and establishes potential on the 35 grid 32a sufficient to render the tube conducting during the half cycle intervals in which the anode 33a is positive with respect to the cathode 34a. As a result during these half cycle intervals current supplied from one terminal of the winding 40 42 of the transformer AT1a flows through the winding of the relay ARE1, resistance AR2 to the anode 33a, thence to the cathode 34a and to the other terminal of the winding 42. As long as the grid potential is maintained, the tube AV1a will 45 be rendered conducting, and current will flow in the winding of the relay ARE1 and effect energization of this relay. The relay ARE1 performs the same function as the corresponding relay in the system shown in Figs. 1A and 1B, controlling the 50 timing means, not shown, and also controlling the wire 20 leading to the interlocking relay, not shown, which controls the crossing signal, not shown.

55 As long as the track section 1T is unoccupied, the flow of current through the track rails is maintained, while the potential on the grid of the tube is maintained with the result that the tube is conducting and the relay ARE1 is energized.

When a train enters the track section 1T from 60 the left, a shunt path is provided between the track rails with resultant deenergization of the track relay 1TR and closing of its contact 58 to complete the circuit to the transformer AT2 of the timing means at station A. At this time, 65 the train not having advanced as far as station A, current continues to flow through the track rails at station A with the result that the potential on the grid of the tube AV1a is maintained, while the relay ARE1 continues to be energized. 70

When the train advances in the track section 1T so that the front of the train is at the right of station A, a shunt path is provided between the track rails 1 and 2 which diverts current from the primary winding 100 of the transformer ATa. 75

As a result the secondary winding 102 will not supply current to maintain the grid potential of the tube AV1a and this tube will be rendered non-conducting and the relay ARE1 will be de-
5 energized.

The supply of current to the transformer ATa will be cut off as long as any portion of the train remains in the portion of track section 1T at the right of station A, and accordingly the relay 10 ARE1 will be maintained deenergized until the train vacates this portion of the track section, whereupon the relay ARE1 will again be energized.

The operation of the system of which the train 15 detecting means shown in Fig. 4 forms a part is substantially the same as that of the system shown in Figs. 1A and 1B and need not be repeated.

20 *Construction and operation of the modification shown in Fig. 5 of the drawings*

In Fig. 5 of the drawings, I have illustrated a portion of a modified form of system embodying 25 my invention. The system shown in this figure is similar to that shown in Figs. 1A and 1B of the drawings as it does not require the use of insulated joints in the track rails at the various train detecting sections, but differs from the systems shown in Figs. 1A and 1B and Fig. 4 as it employs a different form of means for securing current from the track rails to maintain the grid potential on the tubes of the train detecting means. This system employs a tube AV1a of the same 30 type employed in the system shown in Fig. 4.

35 Referring to Fig. 5 of the drawings, the equipment at station A includes a loop 110 mounted between the track rails 1 and 2 and having relatively long side portions located adjacent to the track rails 1 and 2 and extending substantially parallel thereto so that the loop is in inductive relationship to the track rails. The loop 110 is shown as comprising two complete turns, but it will be understood that any suitable number of turns may be employed, and it is contemplated 40 that a substantially larger number of turns will be employed so that an effective inductive coupling will be obtained between the loop and the track rails.

45 The ends of the loop 110 are connected to the terminals of the primary winding 111 of the transformer ATb. The secondary winding of the transformer ATb is connected to the elements of the tube AV1a in substantially the same manner that the secondary winding 102 of the transformer ATa of the system shown in Fig. 4 is connected to the tube employed in that system. One terminal of the secondary winding 112 is connected to the anode 33a of the tube AV1a, and the other terminal of the transformer secondary winding 112 is connected through the resistor AR1a to the tube grid 32a.

50 The other circuits employed in the train detecting means shown in Fig. 5 are substantially the same as the corresponding circuits employed 55 in the system shown in Fig. 4 and will not be traced in detail.

55 In the operation of the system shown in Fig. 5, as long as the track section 1T is unoccupied, current supplied by the track transformer, not shown, flows through the track rails 1 and 2 and energizes the control winding 9 of the track relay 1TR.

60 The current flowing through the track rails 1 and 2 induces current in the loop 110 with the 75 result that the loop supplies current to the trans-

former ATb, which in turn supplies current to maintain the potential on the grid 32a of the tube AV1a to render the tube conducting to effect energization of the relay ARE1.

When a train enters the track section 1T from 5 the left and advances in the section far enough that the front of the train is located at the right of station A, current no longer flows in the portions of the track rails paralleled by the loop 110. Accordingly current is not induced in the loop, 10 and the potential on the grid 32a of the tube AV1a is not maintained. As a result the tube is no longer conducting and the relay ARE1 is deenergized.

When the train vacates the track section, cur- 15 rent will again flow through the portions of the track rails adjacent the loop 110, and the grid potential of the tube AV1a will be restored and the tube will again be conducting and will effect energization of the relay ARE1. 20

Construction and operation of the modification shown in Figs. 6 and 7 of the drawings

In Figs. 6 and 7, I have illustrated a portion 25 of another form of train detecting means embodying my invention. This form is shown as incorporating a tube AV1a of the cold cathode type, while the modification shown in these figures of the drawings is adapted for use in non-track circuited territory or where direct current 30 track circuits are employed. This modification does not require the use of insulated joints in the track rails at the various train detecting stations.

The train detecting means shown in Figs. 6 35 and 7 of the drawings does not require the use of a track transformer to supply current to the track rails in the manner contemplated in the system shown in Figs. 1A and 1B of the drawings. Similarly a highway crossing control sys- 40 tem employing train detecting means of the type shown in Figs. 6 and 7 of the drawings does not employ a track relay as is employed in the system shown in Figs. 1A and 1B of the drawings. Instead suitable train detecting means is pro- 45 vided at a point in the track stretch at the left of station A and operative on passage of a train to initiate charging of the condenser incorporated in the timing means, not shown, at station A.

As shown in the drawings, the tube AV1a has 50 its cathode 34a connected to one terminal of the secondary winding 42a of the transformer AT1a, while the other terminal of the transformer secondary winding is connected in series with the winding of the relay ARE1a and a resistor AR1a 55 with the anode 33a of the tube. A condenser AC3 is shunted across the relay winding, while a wire 115 connects one of the track rails, such as the track rail 1, with the circuit leading from the tube anode 33a at a point in that circuit inter- 60 mediate the resistor AR1a and the transformer.

The track rail 1 has associated therewith a member 116, in the form of a length of angle iron supported on the crossties 117 by suitable means, such as supports 118 formed of electrical- 65 ly insulating material. The member 116 is disposed adjacent the inner face of the head of the rail 1, but is spaced far enough therefrom to enable the wheels of the vehicles traveling on the rail to pass without their flanges engaging the 70 member 116, as is clearly shown in Fig. 7 of the drawings. The member 116 is preferably of such length that it will bridge over the space between adjacent wheels of the same truck of a car.

The member 116 is connected by a wire 120 with 75

the grid 32a of the tube AV1a, while a condenser AC2a is connected between the grid and the cathode of the tube AV1a.

The member 116 and the track rail 1 serve as 5 plates of a condenser which is in series with the circuit connecting the tube grid with the transformer secondary winding. The capacity of the condenser formed by the member 116 and the track rail 1 is varied when a train passes through 10 the track section and the flanges of the car wheels extend between the member 116 and the head of the track rail.

In operation, current supplied by the transformer secondary 42a flows in the circuit provided by the condenser AC3, wire 115, the condenser formed by the rail 1 and the member 116, the wire 120 to which is connected the tube grid, and the condenser AC2a.

The various parts of the apparatus are selected so that their values are such that when the track section is unoccupied, the potential impressed on the grid 32a is such that the tube 20 is non-conducting and the relay is deenergized.

The various parts of the apparatus are also 25 selected so that when the capacity of the condenser formed by the track rail 1 and the member 116 is increased as a result of the presence of a wheel flange between the member 116 and the rail head, the potential on the tube grid is 30 such that the tube is conducting. At this time, therefore, the relay ARE1a will be energized. The contact 45 of this relay is arranged to complete the circuit to the crossing signal when the relay is deenergized, and to interrupt this circuit 35 when the relay is energized.

When a train travels past station A, therefore, the tube AV1a will be rendered conducting during the periods in which the flange of a car wheel is present between the member 116 and the head 40 of the track rail. At the times when a wheel flange is not present between the member 116 and the track rail, as when the portion of the car between the car trucks is over the member 116, the tube AV1a is rendered non-conducting, but it again becomes conducting as soon as the flange 45 of a car wheel passes between the member 116 and the rail head. During passage of a train, therefore, the tube AV1a is intermittently rendered conducting, while the relay ARE1a is periodically energized. The relay ARE1a has a slow 50 releasing characteristic so that it will remain picked up somewhat longer than the time intervals between the periods of conductivity of the tube AV1a. During movement of a train past station A, therefore, the relay ARE1a will remain 55 picked up, but it will release promptly as soon as the train passes beyond this point.

The train detecting means shown in this figure of the drawings may be employed in connection 60 with timing means of the type shown in Figs. 1A and 1B. If it is to be so employed, the circuits controlled by the contacts of the relay ARE1a should be arranged so that the circuits which in the system shown in Figs. 1A and 1B are complete or interrupted when the relay ARE1a of that system is energized will be similarly conditioned when the relay ARE1a of the system shown in Fig. 6 is deenergized.

70 Construction and operation of the modification shown in Fig. 8 of the drawings

In Fig. 8 of the drawings I have illustrated still another modification embodying my invention. The equipment shown in Fig. 8 is similar to that 75 shown in Figs. 6 and 7, and does not necessitate

the use of insulated joints in the track rails at the train detecting station. Neither does this equipment require current to be supplied to the track rails by a track transformer, nor does it contemplate the use of a track relay such as is 5 used in the system shown in Figs. 1A and 1B of the drawings.

The system shown in Fig. 8 employs a transformer 125 mounted between the track rails. The transformer 125 has a generally U-shaped core 126 formed of suitable magnetic material. The arms of the core 126 have elongated head pieces extending parallel to the track rail. The core 126 is supported from the crossties by suitable means, not shown, so that the head pieces 10 of the core are disposed adjacent to the inner face of the head of the track rail 1, but far enough away from the rail head to permit the flanges of the car wheels to pass freely between the core and the rail head. The adjacent ends 20 of the head pieces are spaced apart a substantial distance so that an air gap of sufficient width is present between them to substantially prevent flow of magnetic flux directly across this space.

One arm of the core 126 has the primary winding 128 mounted thereon. This winding is connected to the branches of the wires 12 and 14, and thereby to the same source of alternating current as the primary winding 40a of the transformer AT1a.

The other arm of the core 126 has the secondary winding 130 mounted thereon. One terminal of the secondary winding 130 is connected to the grid 32a of the tube AV1a, while the other terminal of the winding 130 is connected in series 35 with a resistor AR1a with the tube anode 33a.

The current supplied to the winding 128 creates magnetic flux in the core 126. Because of the large air gap between the head pieces of the core and between the head pieces and the track 40 rail, the permeability of the magnetic circuit of which the core 126 forms a part is relatively poor. Accordingly on energization of the primary winding 128 little current is induced in the secondary winding 130 with the result that this winding 45 supplies little current to the tube grid circuit.

When a train passes over the portion of the track stretch at station A, the presence of the flange of a car wheel between the core 126 and the rail 1 increases the permeability of the magnetic circuit of which the core forms a part. 50 Similarly, the presence of the heavy iron parts of the car truck above the core 126 provides a magnetic path bridging the gap between the head pieces of the core 126 and thereby increases the permeability of the magnetic path of which the core forms a part. As a result of these increases in the permeability of the magnetic path through the core 126, more current is induced in the secondary winding 130 and there is an increase in 55 the current supplied to the tube grid circuit.

The various parts of the system are selected so that their values are such that when the track stretch is unoccupied, the current supplied by the 60 secondary winding 130 to the tube grid circuit is insufficient to render the tube conducting. At these times, therefore, the relay ARE1a will be deenergized.

The various parts of the system are also selected 70 so that their values are such that when the track stretch is occupied and vehicle trucks are passing over the transformer 125, the current supplied by the transformer secondary winding 130 to the tube grid circuit is sufficient to render the tube 75

conducting. The relay ARE¹a, therefore, will be energized at these times.

The relay ARE¹a, like that employed in the system shown in Fig. 6, has a slow releasing characteristic so that it will not become released on momentary interruptions in the supply of current to its winding, with the result that if the tube is momentarily rendered non-conducting during the time between passage of car trucks over the transformer 125, the relay will remain picked up.

Construction and operation of the modification shown in Fig. 9 of the drawings

15 In Fig. 9 of the drawings, I have illustrated another form of train detecting means embodying my invention. This system is shown incorporating a tube of the type having a heated filament as its cathode. This system differs from 20 certain of the others in that it requires an insulated joint in one of the track rails at each train detecting station.

The system shown in this figure of the drawings has an insulated joint 3 in the track rail 2 at the train detecting station A. This system also includes an impedance transformer 135 having the terminals of its primary winding 136 connected to the rail 2 on opposite sides of the joint 3.

30 One terminal of the secondary winding 137 of the impedance transformer is connected in series with a condenser AC2 with the tube grid 32, while the other terminal of this winding is connected to the center tap of the secondary winding 38 of the transformer AT1, and thereby to the secondary winding 42 of the transformer AT1 and also to the cathode 34 of the tube. The grid of the tube is connected to the other terminal of the transformer secondary winding 40 42 through a resistor AR1.

In the operation of this system current supplied by the secondary winding 42 of the transformer AT1 flows in the grid circuit which is traced from one terminal of the winding 42 through the winding 137 of the impedance transformer 135, condenser AC2, resistors AR1 and AR2, and condenser AC3 to the other terminal of secondary winding 42.

At this time, assuming that the track stretch 50 is unoccupied, the circuit of the primary winding 136 of the impedance transformer 135 is open, and the impedance of this winding is relatively high, while the impedance of the secondary winding is correspondingly high.

55 As a result of the high impedance of the winding 137, there is a relatively large drop in potential between the tube grid 32 and the cathode 34. The various parts of the equipment are chosen so that the grid potential at this time is 60 such that the tube is rendered conducting during the half cycle intervals in which the tube anode is positive with respect to the tube anode. The relay ARE¹, therefore, is energized and it will continue to be energized as long as the track stretch at station A is unoccupied.

When the track section is occupied by a train, the wheels and axles of the vehicles of the train provide connections between the track rails and thereby establish a circuit between the portions 70 of the rail 2 at opposite sides of the joint 3 and thus complete the circuit through the winding 136 of the impedance transformer 135. This circuit may be traced from one terminal of the winding 136 to the track rail 2 at one side of 75 the joint 3, thence to the track rail 1 by the

path through the wheels and axle of a vehicle, along the track rail 1 and back to the track rail 2 through the wheels and axle of a vehicle at a point on the other side of the joint 3, and then to the other terminal of the winding 136.

5 As a result of the completion of this circuit through the winding 136, the impedance of the winding is greatly reduced, while there is a corresponding reduction in the impedance of the winding 137. On this reduction in the impedance of the winding 137 there is a reduction in the difference in potential between the tube grid 32 and its cathode 34. The various parts of the system are chosen so that this reduction in the grid potential is such that the tube is no longer conducting. The relay ARE¹, therefore, is de-energized and remains deenergized as long as the train or a vehicle bridges the joint 3 at station A, while the relay will again be energized when the train no longer bridges the joint 3.

10 The train detecting means shown in this figure of the drawings is adapted to be employed in connection with timing means of the type shown in Figs. 1A and 1B, if desired, to control the operation of a crossing signal in accordance 15 with the speed of the train approaching the intersection protected by the signal.

15 The train detecting means and the timing means to detect the passage of a train through a track stretch and to also measure the speed 20 of the train to thereby determine the point in the track stretch to which the train must advance before operation of the highway crossing signal is initiated.

25 In addition it will be seen that this invention provides several forms of train detecting means and that either of these may be employed in connection with the timing means.

30 While the train detecting means and the timing means have been described in connection with a control system for a highway crossing signal, it should be understood that they are not limited to use in this connection and that it is contemplated that they may be employed wherever the results which they provide are desired.

35 Although I have herein shown and described a complete system for controlling a highway crossing signal, together with several modified forms of train detecting means, it should be understood that various changes and modifications 40 may be made therein within the scope of the appended claims without departing from the spirit and scope of my invention.

45 Having thus described my invention, what I claim is:

50 1. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, a circuit for controlling said crossing signal, the device associated with each of said train detecting stations except the device associated with the station farthest removed from the intersection controlling said circuit, a first and a second timing means also controlling said circuit, the device associated with the station farthest removed from the intersection and the device associated with the station next farthest removed from the intersection jointly controlling the first timing means, the device associated with said station next farthest removed from the inter- 55 60 65 70 75 80 85 90 95

section and the device associated with the adjacent station in advance thereof jointly controlling said second timing means.

2. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, each of said devices except the device associated with the station farthest removed from the intersection controlling a circuit for controlling the crossing signal, timing means comprising a condenser, an element connected in parallel with said condenser and being adapted to become conducting when and only when current of a predetermined potential is supplied thereto, and a relay having its winding connected in series with said element whereby said relay winding is energized when said element is conducting, said relay controlling the circuit for controlling the crossing signal, means controlled by the device associated with the station farthest removed from the intersection for initiating the supply of current to the circuit of said condenser and said element, and means controlled by the device associated with the station next farthest removed from the intersection for interrupting the supply of current to the circuit of said condenser and said element.
3. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, each of said devices except the device associated with the station farthest removed from the intersection controlling a circuit for controlling the crossing signal, timing means comprising a condenser, an element connected in parallel with said condenser and being adapted to become conducting when and only when current of a predetermined potential is supplied thereto, and a relay having its winding connected in series with said element whereby said relay winding is energized when said element is conducting, said relay controlling the circuit for controlling the crossing signal, means controlled by the device associated with the station farthest removed from the intersection for initiating the supply of current to the circuit of said condenser and said element, and means controlled jointly by the train detecting device associated with the station farthest removed from the intersection, the device associated with the station next farthest removed from the intersection, and the relay of said timing means for supplying current over a circuit including said element in series to energize said relay.
4. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, each of said devices except the device associated with the station farthest removed from the intersection controlling a circuit for controlling the crossing signal, timing means comprising a condenser, an element connected in parallel with said condenser and being adapted to become conducting when and only when current of a predetermined potential is supplied thereto, and a relay having its winding connected in series with said element whereby said relay winding is energized when said element is conducting, said relay controlling the circuit for controlling the crossing signal, means controlled by the device associated with the station farthest removed from the intersection for initiating the supply of current to the circuit of said condenser and said element, and means controlled by the device associated with the station next farthest removed from the intersection for interrupting the supply of current to the circuit of said condenser and said element.
5. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, each of said devices except the device associated with the station farthest removed from the intersection controlling a circuit for controlling the crossing signal, timing means comprising a condenser, an element connected in parallel with said condenser and being adapted to become conducting when and only when current of a predetermined potential is supplied thereto, and a relay having its winding connected in series with said element whereby said relay winding is energized when said element is conducting, said relay controlling the circuit for controlling the crossing signal, means controlled by the device associated with the station farthest removed from the intersection for initiating the supply of current to the circuit of said condenser and said element, and means controlled by the device associated with the station next farthest removed from the intersection for interrupting the supply of current to the circuit of said condenser and said element, and means controlled by the device associated with the station next farthest removed from the intersection for dissipating a charge established on the condenser.
6. In combination, a stretch of railway track having an intersection with a highway, a crossing signal for protecting said intersection, a plurality of train detecting stations located at points in said track stretch progressively farther in the rear of said intersection, each of said stations having a train detecting device responsive to the presence of a train in said track stretch at said station, each of said devices except the device associated with the station farthest removed from the intersection controlling a circuit for controlling the crossing signal, timing means comprising a condenser, an element connected in parallel with said condenser and being adapted to become conducting when and only when current of a predetermined potential is supplied thereto, and a relay having its winding connected in series with said element whereby said relay winding is energized when said element is conducting, said relay controlling the circuit for controlling the crossing signal, means controlled by the device associated with the station farthest removed from the intersection for initiating the supply of current to the circuit of said condenser and said element, and means controlled by the device associated with the station next farthest removed from the intersection for interrupting the supply of current to the circuit of said condenser and said element, and means controlled by the device associated with the station next farthest removed from the intersection for dissipating a charge established on the condenser.

- of a predetermined potential is supplied thereto, and a relay having its winding connected in series with said element whereby said relay winding is energized when said element is conducting, 5 said relay controlling the circuit for controlling the crossing signal, means controlled by the device associated with the station farthest removed from the intersection for initiating the supply of current to the circuit of said condenser and said element, means controlled by the device associated with the station next farthest removed from the intersection for interrupting the supply of current to the circuit of said condenser and said element, and means controlled jointly by the 10 device associated with the station farthest removed from the intersection, the device associated with the station next farthest removed from the intersection, and the relay of said timing means for supplying current to energize said 15 relay.
7. In combination, a stretch of railway track having an intersection with a highway, a crossing signal for protecting said intersection, a plurality of train detecting stations located at points 20 in said track stretch progressively farther in the rear of said intersection, each of said stations having a train detecting device responsive to the presence of a train in said track stretch at said station, each of said devices except the device 25 associated with the station farthest removed from the intersection controlling a circuit for controlling the crossing signal, timing means comprising a condenser, an element connected in parallel with said condenser and being adapted to become 30 conducting when and only when current of a predetermined potential is supplied thereto, and a relay having its winding connected in series with said element whereby said relay winding is energized when said element is conducting, said relay 35 controlling the circuit for controlling the crossing signal, means controlled by the device associated with the station farthest removed from the intersection for initiating the supply of current to the circuit of said condenser and said element, means controlled by the device associated 40 with the station next farthest removed from the intersection for interrupting the supply of current to the circuit of said condenser and said element, and means controlled jointly by the device associated 45 with the station farthest removed from the intersection, the device associated with the station next farthest removed from the intersection, and the relay of said timing means for supplying current over a circuit including said element 50 in series to energize said relay, said means supplying current of a potential only sufficient to maintain the element conducting, and insufficient to render the element conducting if it is not already in such condition.
8. In combination, a stretch of railway track 55 having an intersection with a highway, a crossing signal for protecting said intersection, the rails of said track stretch having insulated joints therein to form a track section extending to the rear of said intersection, a source of alternating current of one frequency, means for connecting said source of alternating current to said track rails at a point in said track section adjacent said intersection to thereby supply alternating current to a track circuit including the track rails of said track section in series, train detecting means comprising an electronic tube having an anode, a cathode and a grid, means for establishing a potential difference between the tube anode and cathode, means in inductive relation-

ship with at least one of said track rails and receiving current therefrom for establishing a potential on said tube grid, and means responsive to current flow between said tube anode and cathode for controlling said crossing signal. 5

9. In combination, a stretch of railway track having an intersection with a highway, a crossing signal for protecting said intersection, the rails of said track stretch having insulated joints therein to form a track section extending to the rear of said intersection, a source of alternating current of one frequency, means for connecting said source of alternating current to said track rails at a point in said track section adjacent said intersection to thereby supply alternating current to a track circuit including the track rails of said track section in series, train detecting means comprising an electronic tube having an anode, a cathode and a grid, means for establishing a potential difference between the tube anode and cathode, means inductively coupled with one of the track rails and receiving energy inductively from said rail for establishing a potential on the tube grid to render the tube conducting, said last named means including a circuit shunting said tube grid and resonant to current of a frequency other than said one frequency to thereby divert such other current from said tube grid to prevent unintended changes in potential on said grid, and means responsive to current flow between said tube anode and cathode for controlling said crossing signal. 30

10. In combination, a section of railway track having a pair of track rails over which traffic moves in a given direction, a track circuit for 35 said section comprising means for supplying alternating current to the track rails at the exit end of the section and a track relay for detecting entrance of a train into said section, said relay having a winding receiving current from the track rails at the entrance end of the section, an electronic tube having an anode, a cathode and a grid, means for establishing a potential difference between the tube anode and cathode, a coil inductively coupled with one of the 40 track rails of said section at an intermediate point in said section and receiving energy inductively from said rail, a circuit including said coil for establishing a potential on the tube grid to render the tube conducting when and only when current supplied at the exit end of said section 45 flows in the portion of the track rail with which said coil is coupled, whereby said tube is conducting when and only when the portion of the track section in advance of said coil is unoccupied, and a device responsive to flow of current between said tube anode and cathode for detecting the presence of a train in advance of said intermediate point in said section. 50

11. In combination, a section of railway track 60 having a pair of track rails over which traffic moves in a given direction, a track circuit for said section comprising means for supplying alternating current to the track rails at the exit end of the section and a track relay for detecting 65 entrance of a train into said section, said relay having a winding receiving current from the track rails at the entrance end of the section, and a plurality of train detecting stations at points progressively farther in advance of the 70 entrance end of said section, each of said stations having an electronic tube having an anode, a cathode and a grid, means for establishing a potential difference between the tube anode and cathode, a coil inductively coupled with one of 75

the track rails at a point adjacent said station and receiving energy inductively from said rail, a circuit including said coil for establishing a potential on the tube grid to render the tube conducting when and only when current supplied at the exit end of said section flows in the portion of the track rail with which said coil is coupled, whereby the tube associated with each train detecting station is conducting when and only when the portion of the track section in advance of said station is unoccupied, and a device responsive to flow of current between the tube anode and cathode for detecting the presence of a train in said section in advance of said

15 station.

12. In combination, a stretch of railway track over which traffic moves in a given direction and having an intersection with a highway, a crossing signal for protecting said intersection, 20 the rails of said track stretch having insulated joints therein to form a track section extending to the rear of said intersection, a track circuit for said track section comprising means for supplying alternating current to the track rails at 25 the exit end of the section and a relay having a winding receiving current from the track rails at the entrance end of the section to detect entrance of a train into said section, a plurality

of train detecting stations at intermediate points in said track section to detect movement of a train to points progressively farther in advance of the entrance end of the track section, each of said stations having an electronic tube having an anode, a cathode and a grid, means for establishing a potential difference between the tube anode and cathode, a device responsive to flow of current between the tube anode and cathode, a coil inductively coupled with one of the track rails at a point in said section adjacent said station and receiving energy inductively from said rail, a circuit including said coil for establishing a potential on the tube grid to render the tube conducting when and only when current supplied at the exit end of said section flows in the portion of the track rail with which said coil is coupled, means controlled jointly by said relay and by the device associated with the train detecting station farthest removed from the intersection for controlling said crossing signal, and means controlled jointly by the device associated with said station farthest removed from the intersection and the device associated with the station next farthest removed from the intersection for also controlling said crossing signal. 5 10 15 20 25
